Primary Examiner—A. Hugo Word*Assistant Examiner*—Doris V. Coles*Attorney, Agent, or Firm*—Millen, White & Zelano**[57] CLAIM**

The ornamental design for an armrest for stabilizing a fishing rod, as shown and described.

DESCRIPTION

FIG. 1 is a front elevational view of an armrest for stabilizing a fishing rod, showing my new design;

FIG. 2 is a rear elevational view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a perspective view thereof; and,

FIG. 8 is another front elevational view. The broken line showing a fishing reel and part of a rod is for illustrative purposes only and forms no part of claimed design.

FIG. 1

FIG. 2

FIG. 3

FIG. 4

FIG. 5

FIG. 6

FIG. 7

FIG. 8
